United States Patent Office

Des. 212,851
Patented Dec. 3, 1968

212,851

WIRELESS INTERCOM

Jack C. Roberts, Malibu, Calif., assignor to Saxton Electronics Corporation, Congers, N.Y., a corporation of New York

Filed Feb. 13, 1968, Ser. No. 10,562

Term of patent 14 years

(Cl. D26—14)

FIG. 1 is a perspective view of a wireless intercom showing my new design;

FIG. 2 is a side elevation thereof;

FIG. 3 is a rear elevation thereof;

FIG. 4 is a top plan view thereof; and

FIG. 5 is a perspective view as seen from the bottom of FIG. 1 and taken at a reduced scale.

I claim:

The ornamental design for a wireless intercom, substantially as shown and described.
